(57) **CLAIM**

The ornamental design for a hamburger press, as shown and described.

DESCRIPTION

FIG. 1 is an isometric view of a hamburger press showing my new design:

FIG. 2 is a top plan view thereof;

FIG. 3 is a front elevational view, the rear elevation being a mirror image thereof;

FIG. 4 is a side elevational view, the opposite side being a mirror image thereof;

FIG. 5 is a bottom view thereof;

FIG. 6 is an exploded isometric view thereof;

FIG. 7 is a top plan view of a ram portion illustrated in FIG. 6;

FIG. 8 is a front elevational view of the ram portion: the rear elevation being a mirror image thereof;

FIG. 9 is a side elevational view of the ram portion. the opposite side being a mirror image thereof;

FIG. 10 is a bottom view of the ram portion;

FIG. 11 is a top plan view of a lifter illustrated in FIG. 6;

FIG. 12 is a front elevational view of the lifter, the rear elevation being a mirror image thereof;

FIG. 13 is a side elevational view of the lifter, the opposite side being a mirror image thereof;

FIG. 14 is a bottom view of the lifter;

FIG. 15 is a top plan view of a cavity portion illustrated in FIG. 6;

FIG. 16 is a front elevational view of the cavity portion, the rear elevation being a mirror image thereof;

FIG. 17 is a side elevational view of the cavity portion, the opposite side being a mirror image thereof; and,

FIG. 18 is a bottom view of the cavity portion.

The broken line showings form no part of the claimed design.

The ram, lifter and cavity portions are shown separately for clarity of illustration.
